UNITED STATES PATENT OFFICE.

CHARLES H. OSLUND AND JOHN E. JOHNSON, OF WORCESTER, MASSACHUSETTS, AS
SIGNORS TO O & J MACHINE COMPANY, OF WORCESTER, MASSACHUSETTS, A
CORPORATION OF MASSACHUSETTS.

LABEL-WIPPING DEVICE.

Application filed January 18, 1925. Serial No. 1,699.

This invention relates to a machine for applying a label all around the neck of a bottle or the like and wiping it down in such a manner that the pressure of the wiping rollers will smooth down all parts of the label and will act to wipe down both ends of the label in such a manner as to insure their sticking tightly to the bottle.

The invention involves the application of the label wiping device to a labelling machine of the rotary table in which the table rotates continuously. We provide two sets of label wiping devices rotating continuously but having a yielding action and so arranged that they will pass between the bottle and the clamping rod which holds it on the table and will wipe the label down from the center towards the two ends without relieving the label from pressure at any time during the wiping operation.

Other objects and advantages of the invention will appear hereinafter.

Reference is to be had to the accompanying drawings, in which—

Fig. 1 is a side view of a rotary table labelling machine partly in central section showing a preferred embodiment of this invention;

Fig. 2 is a plan of the same;

Fig. 3 is a plan of the wipers located over the table showing parts in section and on enlarged scale;

Fig. 4 is a side view of the same with parts in section;

Fig. 5 is a sectional view on the line 5—5 of Fig. 4; and

Figs. 6, 7, 8 and 9 are plan views with the operating parts removed showing various steps in the operation of wiping down a neck label on a bottle by means of this machine.

We have shown the invention as applied to an ordinary rotary table labelling machine of our own construction comprising a table or carrier 10 which rotates continuously with a vertical shaft 11. This table has stations at which the bottles B or other articles to be labelled are clamped down by clamps 12 having clamping rods 13 extending up through the table just behind each bottle. We have shown a part of a labelling device 14 which brings the label over

and places it in front of a bottle and a label grip 15 which grips the label centrally on the front of the bottle and holds it while the bottle is passing around a part of the circumference. These parts are all old and the invention is not necessarily limited to this type of machine but is particularly adapted thereto. On the machine frame 16 is an upward extension 17 and a vertical rod 18. These parts carry a bracket 24.

On the shaft 11 which is driven in any desired way we provide a gear 20 which through gearing and shaft drives a vertical shaft 21 which extends up above the table and is located beyond the circumference. This shaft by bevel gears drives a horizontal shaft 22 and a vertical shaft 23 which hangs down from bearings on the bracket 24 within the circumference of, but above, the table. On each of the shafts 21 and 23 is fixed a collar 25 having an arm 26 projecting out from it. Resting on the collar is a hub 27 provided with an arm 28 secured to the hub by a screw 29 or the like and capable of being adjusted by the screw about a pivot 30 with which it is provided. A light spring 31 extends from the arm 26 to the arm 28. The collar 25 is provided with a stop 32 which projects down against a stop 40 on the collar 25. It will be seen that the collar 25 will rotate with the shaft 23 and that through the spring the rotation of the shaft 23 will carry along the hub 27 behind it. The hub is yieldingly connected with the shaft so that if it meets an obstruction it will be retarded.

From this hub extend radial arms 34 shown here as three in number. These are mounted so that they can be adjusted radially and fixed by set screws 35. On each arm there is a vertical stud 36 having a metal bushing 37 on it to which is fixed a wiping roller R. In the present instance these rollers are cylindrical in shape and of soft material as felt or rubber. They are mounted to freely rotate on the studs 36, being held down by screws 39 so as to be all in the same horizontal plane but each one free to rotate on its own axis.

On the other shaft 31 there are the same devices and the rollers are preferably located in a similar manner about this shaft

and spaced equally apart and three of them being present, although the number is dependent upon the speed of the table and the spacing of the bottles thereon, among other things.

With the parts arranged in the manner shown in these drawings, each of the shafts 21 and 23 makes a third of a turn while the table turns far enough for the bottles to move from any position to the next one. The shafts 21 and 23 rotate in the direction of the arrows near the shafts on Figure 6 and the table is also rotating in the direction of the arrow at its circumference. A bottle marked B in Fig. 6 comes around into a position to engage a roll R on the shaft 21, as shown in that figure. At the same time another bottle B', preferably the next one, which has been through the process, is just receiving its last pressure from a roll R^a on the shaft 23. By the time the table has rotated from the position shown in Fig. 6 to the position shown in Fig. 7, the roller R^a has been left behind by the bottle B' and has come out of contact with it for that reason and has passed inside the rod 13. The table rotates at a greater surface speed at this point than the rollers. At the same time the rotation of the shaft 21 causes the roller R to be pressed against the label L held to the bottle at the center of the front thereof by the gripper 15. On account of the yielding action and the particular directions of the path of the table and rollers, the result of this is that this roller presses against the label with a yielding pressure all the way along this path and is forced to yield backwardly as indicated by the short arrow in Fig. 6. By the time the table gets to the position shown in Fig. 7, this roller is pressing against the rear end of the label with considerable pressure due to the fact that the spring is now considerably stretched.

But as the table moves along from this position to the position shown in Fig. 8, the bottle moving faster than the driven speed of the roller, the tension on the spring is released and the spring causes the roller to keep up with the bottle and apply pressure to it constantly. That is practically the only effect that has occurred on this side during this part of the rotation. On the inside, so to speak, the roller R^b, which previously has not been mentioned, now comes around in the direction of the arrow and on account of the converging curved paths of this roller and the bottle, it engages the label first in the position indicated in Fig. 8. Now as the table moves forward and also the roller R^b, it passes along over the label and wipes it down the way the other end was wiped down by the other roller.

By the time the parts reach the position shown in Fig. 9, the bottle B has moved be-

yond the roller R and gone out of contact with it and the circular movement of that roller has been fast enough to draw that roller out from between the bottle and the clamping rod so that there will be no contact between these parts. But at this stage the other roller on the inside numbered R^b has yielded and rolled around into position to wipe over the end of the label and lap it over its end that was laid down by the roller R. This is likewise pressed against the label by yielding spring pressure and held in contact with it longer than it would be if the hub 37 were fixed on the shaft 23, thus insuring the pressing down of this label fully at this point and the smooth application of the label to the bottle.

It will be understood that the next bottle B² to come into action will be engaged by the next roller R^b on one side and R^c on the other in the manner that has been described above. The reason for using three rollers on each side is to permit of the rapid operation of the table but the same idea could be carried out with the use of four rollers, or even one, if the speeds were changed accordingly.

Although we have illustrated and described only a single form of the invention we are aware of the fact that modifications can be made therein by any person skilled in the art without departing from the scope of the invention as expressed in the claims. Therefore we do not wish to be limited to all the details of construction herein shown and described but what we do claim is:

1. In a labelling machine, the combination of a carrier for the articles to be labelled movable at a constant speed, a shaft adjacent thereto rotatable on its axis at a constant speed and provided with an arm having a freely rotatable wiping roller thereon, and yielding means for connecting the arm with the shaft, whereby the arm can lag behind the shaft if it meets an obstruction, the parts being so positioned that as an article to be labelled moves around it will come into contact with said roller at a point on one side and will cause the roller to lag behind and engage the end of a label on the article at the rear thereof and will remain pressed against the end of the label while the carrier is moving so as to insure the laying of that end of the label down smoothly on the surface of the article.

2. In a labelling machine, the combination with a travelling carrier for the articles to be labelled, of a rotary shaft, means for rotating said shaft, an arm extending from said shaft and having a freely rotatable wiping roller thereon for engaging an article to be labelled on the carrier, the direction of rotation of the shaft being such that the roller moves in the general direction in which the article moves on the car-

rier but at a slower rate of speed, and yielding means for connecting the roller with the shaft, whereby when the roller engages the forward side of the article to be labelled, the 5 article will pass beyond it and force the roller to move more slowly in such a manner as to hold the label down on the article until the roller engages the rear side thereof, and, when released by the normal motion 10 of the article on the conveyor, the roller will resume its normal position.

3. In a labelling machine, the combination with a carrier for the articles to be labelled, a shaft adjacent thereto provided with an 15 arm having a freely rotatable wiping roller, and means for rotating said shaft constantly, yielding means for connecting the arm with the shaft, whereby as an article to be labelled comes into contact with said roller 20 at a point on one side, the roller will lag behind and engage the end of a label on the article at the rear thereof and will remain pressed constantly against the end of the label for a time while the carrier is moving.

25 4. In a neck labelling machine, the combination with a rotary table for supporting bottles to be labelled, of a pair of shafts, one inside the area of the table and one outside, means for rotating said shafts, a collar fixed 30 on each shaft, a spring connected with the collar, a hub freely mounted on each shaft adjacent to the collar and connected with it by said spring, whereby normally the rotation of the shaft will pull the hub around 35 with it but it will be permitted to yield and move more slowly than the shaft at any time, said hub being provided with arms projecting therefrom spaced apart, and a soft surfaced wiping roller located 40 on each of the arms at the same elevation as the neck labels on the bottles carried by the table, said shafts being so located and driven at such speeds that as the table rotates continuously a roller connected with 45 one shaft will first engage the front side of the neck label on the bottle at the point where the label is located and will then move part way around the bottle and press that end of the label down and while that 50 roller is in contact with the end of the label at that point, one of the rollers on the other shaft will engage the label at a forward point and on the opposite side and as the table moves forward will roll down that end of the label and press it against the first end thereof.

5. In a labelling machine, the combination with a rotary table for supporting bottles to be labelled, of a pair of shafts perpendicular to the plane of the table, one 60 inside the area of the table and one outside, means for rotating said shafts at constant speed from the table, a collar fixed on each shaft, a hub freely mounted on each shaft adjacent to the collar, a spring

connecting the hub with the shaft, whereby normally the rotation of the shaft will pull the hub around with it but permit it to yield and move more slowly than the shaft at any time, said hub being provided with 70 three arms projecting therefrom at equal distances apart, and a soft surfaced wiping roller located on each of the arms at the same elevation as the labels on the bottles carried by the table, said shafts being so located and being driven at such a speed that as the table rotates continuously a roller connected with the outside shaft will first engage the front side of the neck of the bottle at the point where the label is located and will then move, as the table moves past, about half way around the bottle and press that end of the label down by a yielding pressure as its shaft is held back by the bottle and while that roller is in contact with the end of the label at that point, one of the rollers on the inside shaft will engage the label at a forward point and on the opposite side and as the table moves forward will roll down that end of the label and press it against the first end with a yielding pressure and with a dwell as the table moves along.

6. In a neck labelling machine, the combination with a rotary table for supporting bottles to be labelled, of a pair of shafts, one inside the area of the table and one outside, means for rotating said shafts, a collar fixed on each shaft, a spring connected with the collar, a hub freely mounted on each shaft adjacent to the collar and connected with it by said spring, whereby normally the rotation of the shaft will pull the hub around with it but it will be permitted to yield and move more slowly than the shaft at any time, said hub being provided with arms projecting therefrom spaced apart, and a soft surfaced wiping roller located on each of the arms at the same elevation as the neck labels on the bottles carried by the 100 table.

7. In a labelling machine, the combination with a rotary table for supporting bottles to be labelled, of a pair of shafts, one inside the area of the table and one outside, means for rotating said shafts, a collar fixed on each shaft, a spring connected with the collar, an arm freely mounted on each shaft and connected with the collar by said spring, whereby normally the rotation of the shaft will pull the arms around with it but it will be permitted to yield and move more slowly than the shaft at any time, and a soft surfaced wiping roller located on each arm at the same elevation as the labels on the bottles carried by the table.

8. In a labelling machine, the combination with a rotary table for supporting bottles to be labelled, of a shaft, means for rotating said shaft, a collar fixed on said

shaft, a spring connected with the collar, an arm freely mounted on said shaft and connected with the collar by said spring, whereby normally the rotation of the shaft will 5 pull the arm around with it but it will be permitted to yield and move more slowly than the shaft at any time, and a soft surfaced wiping roller located on the arm at the same elevation as the labels on the bottles carried by the table.

9. In a labelling machine, the combination with a rotary table for supporting bottles to be labelled, of a shaft inside the area of the table, means for rotating said shaft, 15 a collar fixed on said shaft, a spring connected with the collar, an arm freely mounted on said shaft and connected with the collar by said spring, whereby normally the rotation of the shaft will pull the arm around 20 with it but it will be permitted to yield and move more slowly than the shaft at any time, and a soft surfaced wiping roller located on the arm at the same elevation as the labels on the bottles carried by the table, 25 said shaft being so located and driven at such speed that as the table rotates continuously the roller connected with the shaft will first engage the front side of the label on the bottle at the point where the label 30 is located and will then move part way

around the bottle and press that end of the label down.

10. In a labelling machine, the combination with a rotary table for supporting bottles to be labelled, of a shaft perpendicular 35 to the plane of the table outside the area of the table, means for rotating said shaft at constant speed from the table, a collar fixed on said shaft, an arm freely mounted on the shaft adjacent to the collar, a spring 40 connecting the arm with the shaft, whereby normally the rotation of the shaft will pull the arm around with it but permit it to yield and move more slowly than the shaft at any time, and a soft surfaced wiping 45 roller located on the arm at the same elevation as the labels on the bottles carried by the table, said shaft being so located and being driven at such a speed that as the table rotates continuously the roller on the inside shaft will engage the label at a forward point and as the table moves forward will roll down that end of the label and press it against the first end with a yielding pressure and with a dwell as the table moves 50 along.

In testimony whereof we have hereunto affixed our signatures.

CHARLES H. OSLUND.
JOHN E. JOHNSON.
